Michael S. Johnson

seen clearly in order to permit and improve the adaptation of the compressor to the turbine by adjusting the point of operation as near as possible to the pumping and to the maximum efficiency.

As can be seen (see Fig. 2), a blading constituted by a strip 1 having the shape of a propeller blade, fitted by a spindle 2 at the periphery of the rim of a compressor mobile wheel and liable to rock about the axis OO' of this spindle, the strip 1 being shifted with respect to the axis OO' so that the center of gravity of the blade and the thrust center P of the aerodynamic forces acting on the said blade can be changed in a force F which has its origin at the center thrust of the blade. This force F can be divided into a force F_1 which has its origin on the rotation axis OO' of the blade and a torque $\Gamma = Fx_a$. The factors governing the balance of blades such as these and which can be varied in order to carry out the variation in pitch, according to the invention, are then as follows:

- (1) The torque Γ of the aerodynamic forces having an action on the blades or mobile blades,
- (2) The resisting torque of the compressor,
- (3) The rotation speed of the mobile wheel bearing the blades.

The balance of the above system can be illustrated by the following equation:

$$\Sigma(\text{aerodynamic torque, resisting torque, speed factor}) = 0$$

In the algebraic sum Σ , one of the factors can be equal to zero. The resisting torque can be used directly or through the medium which is proportional to it, for instance the density of the air. Also, the speed factor can be used, either directly or through the medium of the centrifugal force which it originates.

Thus, by a predetermined balance of the various above mentioned factors, a better orientation of the blades can be obtained in order to improve the output of the compressor stages at different rates of speed. As can be seen in the diagram of Fig. 1, the operating point is located at the intersecting point of the turbine characteristic with the characteristic curve of the compressor for a given speed and pitch of blade. For instance, for a same period u_3 if a change in pitch is made from i_2 to i_3 the operating point passes from b to c . The latter being nearer to the pumping (in c') than the point b was (in b'), the efficiency has been improved; the rate of flow and the pressure ratio having increased, the overall power of the machine increases.

On the other hand, some characteristics of the compressors which adapt themselves to the driving turbine are obtained. If, in fact, the pitch of the blades of the turbine was always as in i_1 for instance, it can be seen that starting from a given speed for instance, around the low speeds, the turbine would drive a compressor the operating point of which d would be located out of the characteristic turbine CD and in the pumping (shown in this case by the line EF). In order to permit a correct operation at the selected speeds, a pitch i_2 would have to be adopted giving an operating point e , but, at great speeds this pitch would have the drawback of shifting the operating point to b , in other words in a low efficiency zone. If, on the other hand, there is a possibility, in accordance with the invention, to obtain a pitch i_3 at great speeds only, the result is a better adaptation and therefore a better machine.

Moreover, the invention permits to improve the

accelerations of the turbine. If a change in speed is made from u_1 to u_3 with a same pitch of the blades i_2 for instance, the operating point is shifted from e to b ; if, in unison, and according to the invention, the pitch has been changed from i_2 to i_3 , the point e arrives in c . During the interval in which the speed has been varied, the variation of the mass of fluid passing through the compressor, with the same pitch i_2 can be illustrated by the line $e-b$. With a variation in pitch from i_2 to i_3 , it would be represented by the line $e-c$; during the same interval of variation, the output will therefore have been greater, and later the impulsion given to the turbine will be stronger. This concerns the compressor; for the whole of the machine, the results are multiplied by reciprocal inter-actions.

In the practical form of embodiment of the invention, the variation of the pitch of the blades can be obtained by means of various devices established according to the manufacturer's personal requirements and according to the value of the factors which govern this variation.

In the example illustrated in Figs. 3 and 4, 3 indicates the rim of a mobile wheel of the axial compressor bearing in this case, at the periphery, two rows of blades or small blades 1. Each of these is constituted, according to a method already known and as illustrated in Fig. 2, by a metal strip twisted in the shape of a propeller and having sectionally an aerodynamic profile. According to the invention, each blade is fixed onto the rim 3 through the medium of a spindle 2 mounted on a ball abutment 4 which permits it to rotate partially.

As it has been specified above, each blade being constituted in such a way so that it is shifted with respect to its axis of oscillation, the result is, that when the wheel 3 is driven into a rapid rotary movement, the component of the centrifugal force, in addition to the resultant of the aerodynamic forces which act on the blade, gives an elementary torque Γ which tends to make the blade turn about its axis. A small bevel gear 5 is fixed integrally at the lower part of each blade 1. The wheel 3 bearing the blades 1 is mounted free on a shaft 6 which bears a disk 7, which comprises here, on either side of its peripheral part, two bevel gears, 8^a , 8^b , which respectively engage with the gears fixed at the bases of each row of blades.

The blade bearing 3 and geared disks 7 are interconnected by a connected connecting rod system 9^a and 9^b , one of the ends of which is fixed on axles 10^a , 10^b , borne by each disk, and the other being connected on a common axle 11 bearing a mass 12. The compressor is driven by a central shaft 6 integral with the disk 7. The disk 3 is thus driven in this movement through the medium of the connected connecting rods 9^a and 9^b of the mass 12. If the centrifugal masses are carefully designed, the disk 3 follows the disk 7 with a variable off-set the balance of which is obtained at all times by the constitution of the resisting torque, of the position of the connecting rods, and of the value of the centrifugal force of the mass 12 and of the connecting rods. At all times, the off-set between the disks 3 and 7 depends then of the resisting torque and of the centrifugal force resulting from the rotation speed. Due to the fact that the bases of the blades borne by the disk 3 comprise a gear 5 engaging with the disk 7, it results from this that for any variations of the off-set of the two disks 3 and 7 there corresponds a variation of the pitch of each blade 1. Thus an elementary device is

constituted, permitting to vary the pitch of the blades 1 according to the value of the torque and of the speed.

In order to avoid the sudden strain caused by the accelerations or decelerations and to limit the amplitude of the debatement of the blades, a set of abutments as 13, 14 and 15, fixed respectively on disks 3 and 7 and shock absorbing organs, for example rubbing surfaces interposed between the connecting rods 9^a, 9 and the masses 12.

As it can be understood, in the most general case, in which a compressor comprises several stages, the elementary device described herein above can be employed according to the selected predetermined, either individually to each stage, or in cooperation with a group of stages, or the total stages.

In the modification illustrated in Fig. 5, the centrifugal force of a mass is replaced by the intermediate action of an auxiliary motor using a fluid such as oil. On this figure can be seen in 3 the mobile disk of one stage of an axial compressor, mounted on an axle 6', and bearing on its rim blades 1 mounted in the manner herein before described by means of a spindle 2 with an interplaced ball abutment 4. The disk 3 is here driven rotatively through the medium of a disk 7' pivoting on the axle 13 of the disk 3, but which is prevented from being displaced by lateral abutments 14, 15, the disk 17 being itself driven by a geared part 16 which is integral with it. The junction between the disk 3 and the disk 7' is secured through the medium of a part 17 having the shape of a crown fitted with an inner helical toothed part 18 which meshes with a geared part 19 integral with the disk 7', and of an outer helical toothed part 20 which meshes with an inner toothed part 21 integral with the disk 3. The disk 7 bears, on the other hand, at its periphery, sockets 22 which receive knee joints 23 formed at the ends of levers 24 fixed at the base of each of the blades 1.

The disk 3 comprises, on its inner face, a protruding crown 25 constituting a piston in an annular groove 26 provided in the part 17, the chamber formed between the piston constituted in this manner and the bottom of the socket 26 containing as it will be described later, a fluid such as oil. The inner 18 and outer 19 helical toothed parts of the piece 17 are established so that the driving torque of the compressor determines an axial thrust which is counteracted by a pressure of the fluid admitted in the chamber 26.

The fluid arrives under pressure through an opening 27 provided in the center of the shaft 6' and is guided by a conduit 28 provided in the disk 3 up to a distributing device arranged between the piston 25 and the part 17. This device comprises a slide box, sliding in a series of bores constituting several compartments in the piston 25 and in the piece 17, namely: a first compartment 30 in which ends the canal 28 bringing the fluid, and from where the latter is guided by a canal 31 arranged in the slide box 29 up to the right end of the said slide box; an intermediate compartment 32, in which is fitted a median abutment 33 provided on the slide box 29 and from where starts a canal 34 which returns the fluid 70 to an exit conduit 35 arranged within the axle of the shaft 6'; a compartment 36, arranged in an extension 37 of the piece 17 and in which a collar 38 is fitted, formed at the end of the slide box 29. Between the bottom of the compartment 32 in

the piston 25 and the abutment 33 of the slide box 29 is interplaced a compressed spring 39 which tends to push back the said slide box to the right. On the other hand, the collar 38 of the said slide box comprises a groove 38^a in which issues the conduit 31 mentioned above, and which can place itself opposite a calibrated opening 49 drilled through the wall of the extension 37 of the piece 17 and putting into communication the compartment 36 with the chamber 26. Finally, in the piston, a conduit 41 is arranged, this conduit establishing a communication between the chamber 26 with a hollow part 42 arranged in front of the left end of the slide box 29, while a conduit 43 drilled in the collar 38 of the slide box 29 establishes a communication between the chamber 36 and the chamber 32.

Due to this arrangement, the position of the slide box will be determined by the balance resulting from the action of three forces in unison:

(a) A force proportional to the centrifugal force which is materialized by the force which is exerted on the column of liquid flowing from the servo-motor, through the chamber 32 and returned through the axle of the shaft 6' by the conduit 24.

(b) The elastic force of the spring 39 located in one chamber in communication with the outside through a channel 43;

(c) A force which is proportional to the resisting torque materialized by the pressure of the liquid enclosed between the piston 25 and the piece 17, and the value of which is maintained so as to balance the reactions created by the driving strain of the disks on the helical gears.

The first of these forces acts on the whole surface of the central abutment 33 of the slide box 29. The third acts on the left front end of the slide box 29 through the channel 41. The spring 39 adds its power to one of the two other forces. The resultant of the force proportioned to the speed is opposed to the spring 39, the compression of which determines a definite position of the slide box 29. The calibrated bore 40 drilled in the extension 37 of the part 17 is normally closed by the collar 38 of the slide box, which is submitted, on one hand by its groove 38^a to the motive pressure of the fluid, and on its external right surface is in relation with the draining chamber 32 through the medium of the channel 43. Thus, as it will be noticed, any movement of the slide box 29 causes immediately a correlative shifting of the piece 17, and thereby, through the play of the helical gears 18-19 and 20-21, an angularly relative displacement of the disks 3 and 7'. This movement determines, through the medium of the knee-joint levers 24, a pivoting of the blades 1 about their axis of fixation. Thus a definite pitch of the blades 1 corresponds to each balance position given by the torque and the rotation speed.

Fig. 6 concerns a device which uses an electric servo-motor. The device illustrated in Fig. 6 comprises two stages each of which comprises as above, two disks 3 and 7', one of which, 3, bears on its rim mobile blades 1, and the other, 7', driving the compressor, bears on its periphery sockets 22 in which are engaged knee-joints 23 provided at the end of levers 24 integral with the bases of the blades. The junction between the two plates of each stage is insured by an epicycloidal set of gears the planet wheel carrier of which 14 is integral with the driving plate.

7', the outer crown 45 is fixed onto the blade bearing disk 3, and the planet wheels 46 engage with a central pinion 47 clamped on a shaft 6' located in the axis of the disks 3 and 7', and driven through the medium of a transfer case 48, by an electric motor 49.

A servo motor, located for instance on the casing of the transfer case 48, regulates the movement of the motor 49 and accordingly the off-set between the disks 3 and 7'. This servo motor includes a lever 51 which comprises three connected parts, namely:

A first connected part 51^a on which act, in opposition, on one hand the rotation speed of the compressor, materialized here by the thrust of deadheads 52 submitted to the action of the centrifugal force and driven at a speed proportioned to that of the compressor, and on the other the resisting torque represented by the characteristic factor of the compressed fluid (ratio between the fore and aft depression and the density of the fluid to be compressed) and which is materialized by an aneroid device 53, while a spring 54 sets, for each balance position, a definite position of the connected part 51^a;

A second intermediate connected part 51^b, to which is connected a mobile organ for instance a needle 55 which controls the sensitive element of an electric circuit, for instance the rheostat 56 of a Wheatstone bridge;

A third connected part 51^c, in relation with the central shaft 6', for example through the medium of a tangent wheel and endless screw mechanism 57 driven through the medium of the transfer case 48, so that its position is determined according to the off-set existing between the two disks 3 and 7'.

Due to this arrangement, for any variation of torque or of speed, the balance of the forces exerting a stress on the connected part 51^a is modified. The connecting point 51^c being momentarily fixed, the lever 51, moving about this point, entrains, by the movement of the needle 55, a variation of the resistance 56 and this variation switches on, through the medium of a Wheatstone bridge 58 the electric motor 49. The latter determines a variation in the off-set between the two disks 3 and 7', and consequently a correlative variation of the blades 1. The connecting point 51^c is then driven along in this same movement and returns the lever 51 in a balanced position, cutting off thereby the electric power supply to the motor.

It is to be understood, as it stands out from the hereinabove text, that the invention is not limited in its realizations only to the examples described and illustrated, but can take the form of any other modifications.

I claim:

1. A gas turbine including an axial several stage compressor and a drive shaft driving the said compressor, in which each stage of the said compressor comprises a first rotating disk, spindles mounted at the periphery of said first disk so as to be able to pivot respectively about a radial axis, blades integral individually with each spindle, a second disk mounted co-axially with the said first disk and integral with the first driving shaft, means connecting mechanically the said second disk with each of said spindles, so that a relative angular displacement of the two disks determines correlative a pivoting of the said blades about a corresponding radial axis, and means connecting the said second disk to the first disk so that the first

disk follows the said second disk with an angular offset the balance of which depends, at all times, on the resisting torque and the centrifugal force.

5 2. A gas turbine according to claim 1, in which the said means connecting mechanically the said second disk with each of the said spindles comprise a bevelled geared crown wheel integral with said second disk and a bevel gear clamped on each of the said spindles and meshing with the said bevelled geared crown wheel.

3. A gas turbine according to claim 1, in which the said means connecting mechanically the said second disk with each of the said spindles comprise a lever fixed on each of said spindles forming a ball at the end of the said lever, the said ball being engaged in a corresponding socket provided on the said second disk.

4. A gas turbine according to claim 1 in which the said means connecting the said second disk to the said first disk comprise pairs of interconnected connecting rods and connected on one hand on the said first disk, and on the other hand, on the said second disk, and weights borne respectively by each of said pairs of connecting rods, the said weights being designed so that the amount of offset between the two disks depends on the centrifugal force exerted on the said weights of the said connecting rods.

5. A gas turbine according to claim 1 in which the said means connecting the said second disk to the said first disk comprise a servo-motor operating through the medium of a fluid.

6. A gas turbine according to claim 1 in which the said means connecting the said second disk to the said first disk comprise a crown wheel helically geared externally integral with the said second disk; a crown wheel helically geared internally integral with the said first disk, an annular piece helically geared internally and externally meshing respectively with the teeth integral with the second disk and of the first disk, an annular extension provided on the first disk and adapted so as to constitute a piston in a corresponding hollow part in the said annular part, a slide box engaged on one hand with the said extension and on the other hand, with the said annular piece, elastic means acting on one hand on the said slide box, the said slide box being moreover under the action of a fluid under pressure admitted in the said hollow part of said annular piece, so that the position of the said slide box and consequently the angular relative position of the said second disk and of the said first disk are determined at all times, by the balance resulting from the simultaneous action of the said elastic means, of the centrifugal force acting on the said fluid and on the pressure of the said fluid.

7. A gas turbine according to claim 1 in which the said means connecting the said second disk to the said first disk comprise an electric servo-motor.

8. A gas turbine according to claim 1 in which the said means connecting the said second disk to the said first disk comprise a planet wheel bearer integral with the said second disk, an internally geared crown wheel integral with the said first disk, planet wheel pinions mounted on said planet wheel bearer and engaging with the said internally geared crown wheel, a central pinion clamped on said driving shaft and engaging with said planet wheel pinions, an electric motor driving said driving shaft, means to control the operation of said electric motor, and mobile elements arranged so as to move under the

action of the speed variations of said compressor, mobile elements arranged so as to move under the action of the variations of the resisting torque and a mobile organ driven simultaneously by the said mobile elements first mentioned and by the said mobile elements mentioned after, so as to control the means controlling the operation of the electric motor.

9. A gas turbine according to claim 1 in which the said means connecting the said second disk to the said first disk comprise a planet wheel bearer integral with the said second disk, an internally geared crown wheel integral with the said first disk, planet wheel pinions mounted on said planet wheel bearer and engaging with the said internally geared crown wheel, a central pinion clamped on said driving shaft and engaging with said planet wheel pinions, an electric motor driving said driving shaft, means including an electric relay controlling the operation of the

10 electric motor, means to control the operation of said electric motor, and mobile elements arranged so as to move under the action of the speed variations of said compressor, mobile elements arranged so as to move under the action of the variations of the resisting torque and a mobile organ driven simultaneously by the said mobile elements first mentioned and by the said mobile elements mentioned after, so as to control the said electric relay.
